UNITED STATES PATENT OFFICE.

ADRIAN SCHIPPER, OF OGDEN, UTAH.

RECHARGEABLE ELECTRIC FUSE.

1,121,876.

Specification of Letters Patent. Patented Dec. 22, 1914.

Application filed January 16, 1914. Serial No. 812,526.

To all whom it may concern:

Be it known that I, ADRIAN SCHIPPER, citizen of the Kingdom of the Netherlands, residing at Ogden, in the county of Weber, 5 and State of Utah, have invented certain new and useful Improvements in Rechargeable Electric Fuses, of which the following is a specification.

This invention relates to an improved 10 and simplified rechargeable electric fuse.

It is the primary object of the present invention to provide an inexpensive, simple and efficient fuse in which the fusible conductor can be quickly and readily replaced 15 by a second conductor of the same predetermined carrying capacity.

A further object of the invention contemplates the provision of means in the nature of a resilient fusible conductor or strip, 20 whereby a perfect contact is at all times insured; the degree of contact being variable by adjustment of the terminal contacts or caps employed in connection with the improved device.

25 The invention still further resides in the provision of a properly ventilated rechargeable electric fuse wherein means is provided for the ultimate escape of inevitable smoke and gas occasioned by the burning 30 of the combustible fuse; this construction eliminating all reasonable possibility of a bursting fuse shell made possible by improper ventilation of the device.

The above and additional objects are accomplished by such means as are illustrated 35 in their preferred embodiment in the accompanying drawings, described in the following specification and then more particularly pointed out in the claim which is appended hereto and forms a part of this application.

In describing my invention in detail reference will be had to the accompanying drawings wherein like characters denote 45 like or corresponding parts throughout the several views, and in which:—

Figure 1 is a longitudinal sectional view of an improved rechargeable electric fuse constructed in accordance with the present 50 invention; Fig. 2 is an end view; Fig. 3 is a section on the line 3—3 of Fig. 1; Fig. 4 is a section on the line 4—4 of Fig. 1; Fig. 5 is a longitudinal sectional view of one of the terminal caps or contacts; Fig. 6 is a 55 longitudinal sectional view of one of the shell supporting terminal caps; Fig. 7 is a

longitudinal sectional view of a portion of the shell; and Fig. 8 is a detail perspective view of the fusible conductor, the dotted lines indicating the fuse formation, when in use. 60

Referring now to the drawings by numeral, 1 designates, as an entirety, the usual tubular or cylindrical shell, in the present instance of any suitable insulating material. 65 The terminals of the shell 1 are exteriorly threaded as at 2 to provide for the reception of terminal caps 3, interiorly threaded, and having concentric elongated openings 4 formed therein, the openings of the said 70 cap being alined. Outer terminal caps or contacts 5 have been provided, the said caps being interiorly threaded as at 6 to provide for the arrangement of the said contacts over the caps 3 above referred to, the said 75 caps 3 being exteriorly threaded as at 7 to render adjustment of the contacts 5 optional according to the degree of contact desirable, this contact variation being effected in a manner to be hereinafter fully 80 described. Asbestos, or other non-combustible packing is inclosed within the shell 1, the fusible conductor or strip 8 being surrounded thereby. The terminals of the conductor 8 project exteriorly of the caps 3 85 through the openings 4 formed therein, from which arrangement, it is apparent that the said terminals may be set at an angle by reason of the forced engagement of the contacts 5 therewith. The fusible 90 conductor 8, being resilient, it is further apparent that the degree of contact between the said conductor and the contacts 5 may be varied by the adjustment of the latter upon the exteriorly threaded terminal 95 caps 3.

Provision has been made for the escape of smoke and gas from the interior of the fuse, after a burning of the conductor 8. With this in view, the openings 4 of the terminal 100 caps 3 are enlarged as at 9 to open communication between the interior of the shell 1 and the exterior of the said caps 3. The escape of the smoke and gas from the interior of the shell 1 being made possible by the openings 9, it is only necessary to provide one or more openings 10 in the terminal caps or contacts 5 to render the escape of the said 105 smoke and gas complete, as well as to provide for the proper ventilation of the fuse. 110 A lining of pressed asbestos 10' may be arranged to inclose the packing surrounding

the fuse 8, the said lining forming a protecting element for the shell 1 when the fuse burns out. This lining is particularly adaptable in using the fuse as a conductor 5 of electricity of high voltage. If desired, blades 11 may be formed integrally with the contacts 5 for an obvious purpose.

To replace the fusible conductor, the same having been destroyed by an excessive current, the terminal caps or contacts 5 are first removed so that the caps 3 may be unscrewed and the burnt fuse withdrawn from either end of the shell. The shells can then be emptied of the non-combustible insulating material. A new fusible conductor of the same carrying capacity is then arranged concentrically within the shell, the extremities of the said conductor projecting exteriorly of the caps 3, which are threaded 15 upon the shell, through the openings 4 formed therein. Previous to the arrangement of the caps over the extremities of the shell, the packing or non-combustible material is replaced. The contacts 5 are then 20 threaded upon the caps 3 until forced into engagement with the terminals of the conductor 8, whereupon a continued turning of the said contacts will cause the said conductor terminals to be bent as indicated in Fig. 25 1 of the drawings to thereby render positive the engagement between the said contacts and the said fuse. When thus arranged, it is apparent that proper ventilation is made possible by the provision of the 30 enlarged openings 9 and the openings 10.

From the above, taken in connection with the accompanying drawings it will be noted that the degree of contact between the fuse 8 and the contacts or caps 5 is variable by the 35 adjustment of the latter upon the terminal caps 3; that the terminal caps 3 serve, not only as a support for the conductor 8, but also as retaining elements for the contacts 5, the latter being threaded thereupon; and 40 that by the provision of the structure above recited, the recharging of an electric fuse 45

is made not only possible but practical, as the cost of manufacture of a fuse constructed as above disclosed is reduced to what is thought to be, the minimum.

50

It will be understood that the above description and accompanying drawings comprehend only the general and preferred embodiment of my invention and that various minor changes in details of construction, proportion and arrangement of parts may be made within the scope of the appended claim and without sacrificing any of the advantages of my invention.

55

Having thus fully described my invention, what I claim as new and desire to secure by Letters Patent, is:—

In a rechargeable electric fuse, an outer shell, a fusible conductor arranged concentric to the shell, an exteriorly and interiorly threaded cap engageable with each shell extremity, each cap having a slot like opening formed therein through which the respective terminals of the conductor extend, the openings of the cap being of a size approximately 65 that of the conductor in cross section, each opening being enlarged to provide an outlet opening for the resulting smoke subsequent to a burning of the fuse, interiorly threaded 70 terminal contacts in cap form adjustable relatively to the terminal caps aforesaid, said contacts being movable relatively to each other and into and out of contact with the respective conductor terminals, the latter being in yieldable frictional contact 75 therewith, an extension integral with each terminal contact, each contact having a plurality of outlet openings formed therein out of registry with the outlet opening of the cap aforesaid, as and for the purpose set 80 forth.
